UNITED STATES PATENT OFFICE

2,452,332

NAIL HOLDING TOOL

Paul Siptrott, New York, N. Y.

Application December 12, 1947, Serial No. 791,215

3 Claims. (Cl. 1—47)

1

This invention relates to new and useful improvements in nail holding tools, and it has for its object to provide a tool that is light of weight and easy to operate.

The said device has a wide scope of usefulness, as it may not only serve the need of mechanics, and people working in their private hobby-shops, but it may, also, and in particular, be of use and great service to those who operate within a narrow space.

Another object of the invention is to provide a tool, which, due to its easy operability, will discourage people in general from attempting to drive a nail held by the fingers, into an object, with the danger of getting hurt during such operation.

The device is extremely simple of construction, as it consists of only three parts, that is, two side members which are spotwelded onto a suitable spring.

The side members appear in shape as finger-like nail holding prongs, curved in a manner so as to provide a convenient grip on the device, which in itself is very compact and easy to carry, and which may be manufactured at an insignificant cost.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is an elevational top plan view of my device.

Figure 2 is a transverse sectional view, taken on the line 2—2 in Figure 1.

Figure 3 is a detail view showing a spring, forming part of my device; while

Figure 4 is a perspective view of my said device.

Referring more particularly to the drawing, the numerals 10, 10 indicate two members, each of which are provided with curved portions 11, 11, so as to form a suitable handle-grip during operation of the tool.

Each of the members 10 are made with elongated slightly bent and tapered end portions 12

2

which, in turn, terminate in a straight and flat horizontal portion 13 formed with graduated indentations 14, 15, 16, so that when the said members 10, 10 are joined together, as shown in Figure 1, different sizes of nails may be held between the two terminal end portions. The said members 10, 10 are held together in springy relationship by means of a spring 17 having the shape as the numeral 3 with elongated wing portions 18. Said spring is spotwelded, as shown at 19 beneath the curved surfaces 11, 11 of the members 10, 10, thus giving a lever effect to the handle of the tool in operation.

It is obvious that changes may be made in the form, construction and arrangement of the several parts, as shown, within the scope of the appended claims, without departing from the spirit of the invention, and I do not, therefore, wish to limit myself to the exact construction shown and 20 described herein.

What I claim as new, and desire to secure by Letters Patent of the United States, is:

1. A nail holding tool comprising two members, having curved portions to form a handle-grip, 25 slightly bent and tapered sections contiguous to the latter, said sections terminate in flat end portions, horizontal relative to said tapered portions, and being formed with graduated apertures therein, and a spring fixedly connecting the two members together.

2. A nail holding tool comprising two members, each of the latter being formed with slightly curved portions upon one side thereof to form a handle-grip, tapered, slightly bent elongations at one end of said members, said elongations terminating in narrow pieces, horizontal with respect to the latter, and being formed with graduated orifices therein, whereby to receive a nail of different dimensions, and a spring securing said 40 two members together.

3. In a device, as claimed in claim 2, and wherein said spring is of a shape substantially like the numeral 3, and being formed with wing-like extensions, whereby to permit a substantial welding of the spring to said two members.

PAUL SIPTROTT.
